DESIGN FOR A WAGON

Charles N. Bourgin, Montclair, N. J.

Application August 11, 1942, Serial No. 107,877

Term of patent 3½ years

To all whom it may concern:

Be it known that I, Charles N. Bourgin, a citizen of the United States, residing in Montclair, in the county of Essex and State of New Jersey, have invented a new, original, and ornamental Design for a Wagon, of which the following is a specification, reference being had to the accompanying drawing, forming part thereof.

Figure 1 is a front elevational view of a wagon showing my new design.

Figure 2 is a side elevational view of the wagon shown in Figure 1.

The rear of the body portion is a solid panel of wood covering the entire back of the receptacle part of the wagon and to which the handle is attached.

I claim:

The ornamental design for a wagon, as shown and described.

CHAS. N. BOURGIN.
